UNITED STATES PATENT OFFICE.

JACOB FRANK, OF CINCINNATI, OHIO, ASSIGNOR TO THE FRANK TEA & SPICE COMPANY, OF CINCINNATI, OHIO, A CORPORATION OF OHIO.

CAN.

Application filed November 5, 1927. Serial No. 231,363.

The invention relates to improvements in can or container tops and particularly to that class for merchandising for domestic use granulated or ground commodities capable of being sifted through apertures or perforations in the can top.

With the present invention the can top is provided with a foraminous portion through which the contents of the can or package can be sifted and an opening preferably of elongated or oval design for pouring out the contents or through which a measuring spoon or the like can be passed, both relatively arranged and capable of being closed or sealed by a single cover or cap preferably of the friction sealing type. The cover has a dished portion fitting into and sealing the opening and providing a scoop or measuring spoon and an extended portion for covering and sealing the foraminous portion of the top and providing a handle for the dished portion.

It is, therefore, an object of the invention to provide a container top with a pour-out opening sealed by a friction cap or cover of dished form with a finger or tongue extension to individually constitute a measuring spoon or scoop.

Another object of the invention is to provide a container top with a pour-out opening and a foraminous portion both sealed by a single cover, the cover adapted to be set in a transposed position sealing the pour-out opening and uncovering the foraminous portion for sifting out the contents of the container, the cover individually constituted and characterized as a measuring spoon or scoop capable of being inserted in the container through the pour-out opening.

Further objects and advantages will be more fully set forth in the description of the accompanying drawings, forming a part of this specification, in which:

Figure 1 is a plan view of the improved can top, showing the cover disposed over both the pour-out opening and the foraminous portion.

Figure 2 is a view similar to Figure 1, but showing the cover transposed for uncovering the foraminous portion.

Figure 3 is a view similar to the previous views, but showing the cover entirely removed.

Figure 4 is a sectional view taken on line

4-4, Figure 1, detailing the entire can construction.

Figure 5 is a perspective view of the cover.

Referring to the drawings which disclose a preferred embodiment, 1 indicates the can body, its upper end marginally flanged, over which the margin 2 of the top 3 is crimped for securing the top to the body. The top has a marginal recess 4 disposed therein for providing a peripheral shoulder 5 against which the flanged end of the can body bears and which is a structural advantage in the crimping over of the top in containers of this class. The channel recess permits the major portion of the top to lie in a plane or level with the top edge of the can instead of being recessed throughout as in the case of the base. Such form of top brings the cap or cover of the friction type above the plane of the top to accommodate for a handle extending from the cover to uncover the perforations when it is desired to sift out the contents of the container.

The illustrated form of can top structure, however, is merely adapted for smaller sizes of containers wherein the dimension would require the handle of the spoon or scoop form of cover or cap to extend slightly beyond the side of the can when in one of its adjusted positions. For large sizes of cans the top may be recessed following the general prevailing methods in the manufacture of cans of this character, and the general formation of the top may follow any design particularly adaptable for other types of crimp joint or union used in connecting the top to the body sides. The can structure herein is one of the conventional types with which the present invention is included and with which it can be utilized without change in the can making machinery now employed.

In an oblong rectangular can the top centrally and toward one side is punched to provide an oblong pour-out opening 6 having a tapering in-turned flange 7 to receive a friction cap or closure, such form of opening likewise being common in cans of this character except usually disposed centrally of a can. Its offset position provides space in the can top for a depressed foraminous portion 8 through which the contents of the can can be sifted, when the pour-out opening 6 is sealed, the depressed portion registering with an extended handle portion of the clo-

sure cap or cover 9 whereby both openings can be sealed by a single cover and by transposing the cover, one of the openings uncovered. The cover is of friction seal type and 5 of dished formation providing a handled measuring bowl and scoop.

The dished or bowl portion of the cover or cap frictionally engages with the flange 7 of the pour-out opening and the handle with 10 the shoulders 10 of the depressed sifter portion 8 so that in the normal position of the cover or cap both the pour-out opening and sifter perforations are simultaneously closed and sealed. For sifting, the cap is set into 15 the pour-out opening in a transposed position with the handle extending in a direction opposite from the foraminous portion, sealing the pour-out opening and uncovering the sifter apertures or perforations. Individually, the cap constitutes a measuring 20 bowl or scoop capable of being projected into the container through the pour-out opening for withdrawing a measured quantity of the contents of the can.

25 The handle may be extended from the dished or bowl portion of the cover in any fashion and need not necessarily form a sealing closure for the recessed foraminous portion as illustrated but merely provide a closure therefor in one setting of the handle, and likewise, the foraminous portion need 30 not be recessed for a permanent sealing can be made by an adhesive tape thereover. For such forms the handle may be represented 35 as a plane tab extension for obtaining an extension finger hold.

The design of the spoon or scoop as a

handled can opening closure may be diversified so that it can, either in its entirety or portion thereof, be utilized as a sealing closure for the opening or openings in the can top. For instance, the handled spoon-shaped cover can be used with the present commercial form of can having a single oblong pour-out opening, thus furnishing 45 the can with a handled bowl of accurate tea or tablespoon measuring capacity, or otherwise proportioned, to meet the universal measuring needs for the kind of commodity packed in the can. 50

Having described my invention, I claim:

1. In a can, a can top provided with an oblong pour-out opening and a cover having a dish portion and handle portion, the dished portion providing a friction closure for said 55 pour-out opening, and the cover individually constituting a handled measure bowl and scoop for measured quantity service of the can contents, and insertable into the can through said pour-out opening. 60

2. A container having a flanged pour-out opening and a foraminous portion for sifting the container contents, and a dished cover having a laterally projecting flat handle on a level with the upper rim of 65 said dished portion, said dished portion fitting frictionally within the flanged opening of the container in only two positions, in one in which the handle forms a closure for the foraminous portion and in the other said 70 foraminous portion is left uncovered.

In witness whereof, I hereunto subscribe my name.

JACOB FRANK.
